CLAIM

The ornamental design for a container for a cosmetic product, substantially as shown and described.

DESCRIPTION

FIG. 1 is a top, front, right, perspective view of a container for a cosmetic product, showing my new design;

FIG. 2 is a bottom, back, left, perspective view of the container shown in FIG. 1;

FIG. 3 is a front elevation view of the container shown in FIG. 1;

FIG. 4 is a rear elevation view of the container shown in FIG. 1, the right and left side elevation views being the same;

FIG. 5 is a top plan view of the container shown in FIG. 1; and,

FIG. 6 is a bottom plan view of the container shown in FIG. 1.

In the drawings, features shown in broken lines form no part of the claimed design.
